UNITED STATES PATENT OFFICE

GISELA DE RIZ, OF VIENNA, AUSTRIA

DESIGN FOR A BICYCLE FRAME

Application filed January 26, 1931. Serial No. 38,449. Term of patent 3½ years.

To all whom it may concern:

Be it known that I, GISELA DE RIZ, a citizen of the Republic of Austria, residing at Vienna VI, Mollardgasse 20, Austria, have invented a new, original, and ornamental Design for Bicycle Frames, of which the following is a specification, reference being had to the accompanying drawings, forming part thereof.

I claim:—

The ornamental design for a bicycle frame, as shown.

In testimony whereof I affix my signature.

GISELA DE RIZ.
